UNITED STATES PATENT OFFICE.

JOHN TAYLOR, OF HAMILTON, ONTARIO, CANADA.

APPARATUS UTILIZED IN SUBAQUEOUS BUILDING CONSTRUCTION.

1,237,582.

Specification of Letters Patent. Patented Aug. 21, 1917.

Application filed February 16, 1914, Serial No. 818,968. Renewed July 5, 1917. Serial No. 178,789.

To all whom it may concern:

Be it known that I, JOHN TAYLOR, a subject of the King of Great Britain, and resident of Hamilton, in the Province of Ontario, Dominion of Canada, have invented certain new and useful Improvements in Apparatus Utilized in Subaqueous Building Construction, of which the following is the specification.

10 This invention relates to sub-surface air working chambers adapted to be utilized in under water construction of dock walls, bridge piers and the like, and the objects of the invention are to facilitate the locating 15 and securing of mechanisms and constructions located under water, to obviate or overcome the use and necessity of coffer dams and the like, to dispense with the use or aid of divers and other objects which will be 20 made clear hereafter, and it consists essentially of the improved construction of apparatus particularly described and set forth in the following specification and accompanying drawings forming part of the same.

25 In the drawings,

Figure 1 is a perspective view of the improved apparatus or device.

Fig. 2 is a sectional elevation of the same.

Fig. 3 is a sectional elevation of the apparatus or device at right angles to that shown in Fig. 2.

Like letters of reference refer to like parts in the several drawings.

Referring to the drawings, A represents 35 the complete apparatus or device comprising the working chamber B, the flotation or water ballast tanks C and the air lock D. The working chamber B is preferably made of wood and is constructed in the form of a 40 rectangular parallelopiped or box open on the bottom side and provided with an air lock D on the top side, entrance to such air lock being gained through the inwardly opening air tight door 1 and thence to the 45 working chamber B through the downwardly opening air tight door 2.

The edges of the doors 1 and 2 are beveled and adapted to engage with the beveled edges 3 provided on the door frame, the 50 doors being suitably mounted on hinges 4 and tightly secured in a closed position in the following manner:—The bolts 5 and 6 are pivotally mounted at one end on the outer and upper faces of the doors 1 and 2, 55 the other end of the said bolts being thread-

ed and adapted to pass through the staples or eye brackets 7 and be secured thereto by means of the wing nuts 8, or in any other suitable manner.

The working chamber is provided with a 60 borrowed light consisting of a wired glass window 9 located in the top face thereof and may be lighted artificially, and is further provided with an internally located ladder 10 so placed as to be convenient to the 65 door 2 and by means of which mechanics can descend into the working chamber in which a suitable adjustable platform 11 is suspended from the eye bolts 12 by means of the block and tackle 13, or in any other 70 like manner.

14 and 15 represent equalizing valves located in the top of the working chamber B and communicating with the air lock D, a further internally located equalizing valve 75 17 and externally located valve 17^a being provided in the top of the air lock and communicating with the atmosphere.

18 represents an air valve located in the top of the working chamber B and communicating therewith, such valve being connected at its outer end by means of the pipe 19 to a low pressure air reservoir or compressor, or any other suitable source of supply suitably located to the working chamber. 80

20 represents a discharge valve located on the top of the working chamber. 21 represents an air pipe extending through the top of the working chamber to the outside thereof, such pipe being connected at its outer 90 end to a high pressure air reservoir or compressor, the other end of the said pipe being provided with a valve 22 adapted to be connected to the pneumatic tools adapted to be utilized in the working chamber.

95 41 represents a pressure gage located on and fixed to the top of the working chamber.

Should the pressure in the chamber B, due to the exhaust from such pneumatic tools, become too great a safety valve 40 is provided on the top of the working chamber. 100 The ballast tanks C extend from the lateral side of the working chamber and are firmly secured or built thereon, such lateral side forming the dividing wall between the working chamber and the ballast tanks, the said ballast tanks being preferably made of wood in the form of a rectangular parallelopiped or box having the top side open to the atmosphere, but which is adapted to carry 110

suitable staging 23 thereon, should such be found necessary or desirable.

The ballast tanks C are further provided with valves 24 which act in the dual capacity of inlet and discharge to and from the said tanks in a manner which will be made clear hereafter, such valves being operated by the spindles 25 rotatably mounted in the brackets 26, the lower end of the said spindle being rigidly secured to the valve 24 and adapted to operate the same by means of the handwheel 27 rigidly mounted on the upper end of the said spindles.

The working chamber B, the ballast tank C and the air lock D are lined internally with sheet metal 28 or the like, suitably secured and fixed thereto in any suitable manner, while to facilitate in communicating with the mechanics in the working chamber 20 a telephone 29 is suitably attached to the outer side of the air lock.

42 represents anchoring legs which are slidably mounted in the brackets 43, such legs being adapted to be lowered and raised by machinery or manually and suitably secured in position. When the legs are in an elevated position they are secured to the brackets 43 by means of pins 44 designed to engage with the orifices 45 in the said legs, and the upper edge of the brackets. While in a lowered position the pins engage with the orifices and the lower edge of the brackets.

In its operation the apparatus or device 35 is floated into a position directly located over the portion of the work it is desired to perform, where it is anchored by lowering the legs 42 to engage with the ground bottom. The valves 24 of the ballast tanks 40 which are located at the lower part of the lateral side of the said tank and below the normal water level, and the outlet or discharge valve 20 located in the top of the working chamber are opened, whereupon the 45 water enters the ballast tanks causing the apparatus to sink to a predetermined level and be partially submerged, the air in the working chamber being discharged through the valve 20 during this operation.

50 When the ballast tanks are filled the valves 24 and 20 are closed and air from the air compressor is now forced into the working chamber through the pipe 19 and valve 18, whereupon the water level in the working 55 chamber is depressed to the desired level exposing the structure on which the desired work is to be done, while at the same time the working chamber and ballast tanks rise partially out of the water thereby causing 60 the water in the said ballast tanks to stand at a different level to the water on the outside of the same.

When it is desired to elevate or raise the apparatus A out of the water the valves 24 65 of the ballast tanks are opened, and since

the level of the water in the ballast tanks is located or stands at a higher level than the water surrounding the said ballast tanks the water will flow from the ballast tanks outwardly, due to this water head, and the resulting lightening of the ballast tanks permits of the buoyancy of the working chamber tending to raise the apparatus, the super-atmospheric pressure in the working chamber at the same time tending to raise the apparatus out of the water until the pressure in the working chamber is reduced to the external or atmospheric pressure.

It should be clearly noted that in the elevating of the apparatus A the valves 24 80 through which the water is discharged from the water ballast tanks acts in coöperation with the super-atmospheric pressure in the working chamber to bring about the desired result.

The depth to which such an apparatus can operate depends entirely on the existing conditions, but it will be understood that the top of the apparatus must at all times be above water and although as here illustrated it only operates to a small depth it will be understood that with slight modifications of construction only, but not of the principle, it can be made to operate to a depth of about sixty feet which is equivalent 90 to two atmospheres super atmospheric pressure, and it is desirable that the pressure in the working chamber should never exceed this pressure which is about a maximum at 95 which life can be sustained and useful work 100 performed.

Any excess of pressure in the working chamber is indicated by the pressure gage 41 and is relieved by setting the safety valve to blow off at a predetermined pressure 105 while should the pressure become excessive and depress the water in the working chamber to the bottom thereof, the air will exhaust under the lower edge of the sides of the said chamber, automatically stabilizing 110 the air pressure and working level of the apparatus.

When the apparatus A is partially submerged to a predetermined depth and it is desired to descend into the working chamber the operator or mechanic opens the door 1 which is securely fastened behind him. The equalizing valve 14 is now opened, whereupon the air pressure in the air lock and the working chamber becomes equal. 120 The door 2 is now opened when the mechanic or operator can descend by means of the ladder 10 into the working chamber, the door 2 being firmly secured in a closed position after entrance has been gained in the 125 working chamber and the equalizing valve 14 closed, and by entering in this way the depressed level of the water in the working chamber is not altered.

It will be seen in the drawing that the lo- 130

5 cation of the equalizing valves and the manner in which they are disposed render it necessary that an assistant should accompany the mechanic or operator who wishes to descend into the working casing whereby the doors and valves may be closed after the said 70 mechanic has descended into the chamber B, but a slight modification of the method of securing the doors would render it possible that no assistant will be necessary to effect entrance or to leave the working chamber B.

10 To facilitate the determining to what depth the working chamber has been submerged a scale is painted on the outer lateral side of one of the ballast tanks while 15 to prevent the pressure rising in the working chamber thereby depressing the water level too much the safety valve 40 is provided and it will be clearly seen that when mechanics 20 are working in such a working chamber under high pressure due to great depth, the safety valve is not only desirable but also essential. Also in entering or leaving the 25 working chamber it is necessary to equalize the pressure first in the air lock to that of the atmosphere, otherwise the door 1 could not or would only under great difficulty be opened, the same holding good with respect to the door leading from the air lock to the 30 working chamber, and incidentally it would be very injurious to the mechanics to go from a low to a high pressure unless by 35 gradually changing such pressure.

40 Since it is desirable that the levels of the 35 under water construction should be clearly defined and determined a water gage 50 is provided in the working chamber whereby it is possible to permit the finished construction being definitely fixed relatively to the 40 normal water level.

45 The apparatus is adapted to be made of wood for light work to a small depth, but when considerable depth resulting in a high pressure are to be negotiated it will be clear 50 that wood and steel or steel alone will be utilized in the construction.

55 As many changes could be made in the above construction and many apparently widely different embodiments of my invention, within the scope of the claims, constructed without departing from the spirit or scope thereof, it is intended that all matter contained in the accompanying specification and claims shall be interpreted as 60 illustrative and not in a limiting sense.

What I claim as my invention is:

65 1. A device of the class described comprising a working chamber open at the bottom and adapted to be lowered over sub-aqueous 70 construction, ballast tanks mounted on the working chamber and open to the atmosphere on the top, and means for alternately filling and emptying the tanks with water ballast without the use of pumps.

65 2. A device of the class described com-

75 prising a working chamber open at the bottom, ballast tanks mounted on the working chamber and open to the atmosphere on the top, means for supplying air to the working chamber and means for alternately filling 70 and emptying the ballast tanks as the air pressure in the working chamber is changed.

3. A device of the class described comprising a working chamber open at the bottom, ballast tanks mounted on the working 75 chamber and open to the atmosphere on the top, means for supplying air to the working chamber, valve means designed to alternately fill and empty the ballast tanks as the air pressure in the working chamber is 80 changed, and means for operating said valve means.

4. A device of the class described comprising a working chamber open at the bottom, and adapted to be lowered over sub-aqueous construction, ballast tanks on the working chamber, open to the atmosphere on the top, means for alternately filling and emptying the ballast tanks, and means for simultaneously anchoring and supporting 90 the working chamber from the ground bottom.

5. A device of the class described comprising a working chamber open at the bottom and adapted to be lowered over sub-aqueous construction, ballast tanks on the working chamber, means for alternately filling and emptying the ballast tanks, brackets 95 on the ballast tanks, legs slidably mounted in the brackets and means for securing the 100 legs in a fixed position.

6. A device of the class described comprising a working chamber open at the bottom and having a window in the upper end, ballast tanks on the working chamber having 105 a sheet metal lining, means for supplying air to the working chamber, means for alternately filling and emptying the ballast tanks as the air pressure in the working chamber is changed and means for entering 110 the working chamber.

7. A device of the class described comprising a working chamber open at the bottom, an air lock operatively mounted on the working chamber, means for supplying air 115 pressure to the working chamber, means for equalizing the air pressure in the working chamber and air lock, means for equalizing the air pressure in the air lock with the atmospheric air, ballast tanks on the working 120 chamber open to the atmosphere on the top and means for alternately filling and emptying the ballast tanks as the air pressure in the working chamber is changed.

8. A device of the class described comprising a working chamber adapted to be lowered over sub-aqueous construction, means for supplying air to the working chamber, means for keeping the air in the working 125 chamber at a predetermined pressure, means 130

for determining the depth of the sub-aqueous construction below the normal water level, ballast tanks on the working chamber open to the atmosphere on the top and means for alternately filling and emptying the ballast tanks as the air pressure in the working chamber is changed.

In witness whereof I have hereunto set my hand in the presence of two witnesses.

JOHN TAYLOR.
